UNITED STATES PATENT OFFICE.

HUGH DONOHOE, OF NEW YORK, N. Y.

SAFETY APPLIANCE FOR DUMB-WAITERS.

SPECIFICATION forming part of Letters Patent No. 718,328, dated January 13, 1903.

Application filed June 5, 1902. Serial No. 110,298. (No model.)

To all whom it may concern:

Be it known that I, HUGH DONOHOE, a citizen of the United States, and a resident of the city of New York, borough of Manhattan, in 5 the county and State of New York, have invented new and useful Improvements in Safety Appliances for Dumb-Waiters, of which the following is a full, clear, and exact description.

10 My invention relates to dumb-waiters, my more particular object being to produce a safety appliance for the purpose of preventing the waiter from falling in the case of breakage of the hoisting-cable.

15 Reference is to be had to the accompanying drawings, forming a part of this specification, in which similar characters of reference indicate corresponding parts in all the figures.

Figure 1 is a central section showing a dumb-b 20 waiter equipped with my invention. Fig. 2 is a somewhat similar view, but showing the parts in a different position; and Fig. 3 is a fragmentary inverted plan view of a part of the mechanism shown in the upper left-hand 25 corners of Figs. 1 and 2, respectively.

The waiter-shaft is indicated at 1 2 and is provided with vertical guides 3 in the usual manner. The waiter proper is indicated at 4 and is actuated by a hoisting-cable 5, sub- 30 stantially in the usual manner. The stationary cable 6, parallel with the shaft and with the hoisting-cable, is provided for the purpose of holding the waiter in case the hoisting-cable breaks. Mounted at a convenient 35 point upon the ceiling of the waiter is a bracket consisting of a heart-shaped plate 7, secured in position by means of screws 8 9 10 and provided with depending flanges 11 11. This bracket has a shoe 12 integrally mounted 40 thereon and provided with an arc-shaped guide 13, the shoe and guide together completely encircling the stationary cable 6.

A lever 14 is pivoted at 15 upon the bracket between the flanges 11 11 and is provided with 45 a shoe 16 for the purpose of directly engaging the stationary cable 6. Upon a pivot 17 is mounted another lever 18, this lever being provided with a revoluble roller 19, the lever being free to move radially upon the pivot 50 17, so that said revoluble roller 19 is free to actuate the lever 14 whenever the lever 18 is moved. The lever 18 is provided at its so-

called "free" end with an aperture 20, and a bolt 21, provided with an eye 22, projects through the aperture 20 and is engaged by 55 nuts 23. A spiral spring 24 surrounds a part of the bolt 21 and normally presses upon the lever 18. A substantially bell-shaped bracket 25 is mounted centrally in the top of the waiter, as shown, and the upper end of the 60 spiral spring engages the said bracket internally, as indicated in Figs. 1 and 2.

The operation of my device is as follows: When the weight of the waiter is thrown upon the free end of the lever 18, this end is moved 65 upward, thereby compressing the spring 24, as indicated more particularly in Fig. 1. With the lever in this position the several parts exercise their usual relation to each other—that is to say, whether the waiter be raised or lowered the spring 24 is usually compressed, as indicated in Fig. 1. If, however, the hoisting-cable 5 is broken, the elasticity of the spring 24 immediately asserts itself, the long or free end of the lever 18 is instantly thrown 70 down, and the revoluble roller 19 is forced into engagement with the lever 14, thereby pressing the shoe 16 into contact with the stationary cable 6, thus locking the waiter upon the stationary cable. It will be noted, therefore, that the two levers 14 and 18 constitute 75 when taken together a compound lever in which the pressure is progressive—that is to say, the greater the downward movement of the free end of the lever 18 the harder will be 80 the pressure exerted by the shoe 16 upon the stationary cable. It will be understood, of course, that the shoe 12 is provided internally with a friction-surface against which the cable 6 bears when the cable is pressed 85 upon by the shoe 16.

By comparing Figs. 1 and 2 it will be noted that in Fig. 1 the revoluble roller 19 is nearer the shoe 16 and farther from the pivot 15 than is the case in Fig. 2. From this fact it follows that the pressure exerted by the shoe 16 90 varies with the radial position of the lever 18 and is progressive.

Having thus described my invention, I claim as new and desire to secure by Letters 95 Patent—

A safety device for dumb-waiters, comprising a movable longitudinal member for hoisting the waiter, a stationary longitudinal mem-

ber disposed parallel with the path of said waiter, a bracket mounted upon said waiter and provided with a friction-surface for engaging said stationary member, a lever mov-
5 ably mounted upon said bracket and provided with a shoe for engaging said stationary lon-
gitudinal member, a second lever pivoted upon said bracket and provided with a revo-
luble roller for engaging said first-mentioned
10 lever, a spring for normally pressing said sec-
ond-mentioned lever into engagement with

15 said first-mentioned lever, and means for connecting said second-mentioned lever with said movable longitudinal member and for hoisting the waiter.

In testimony whereof I have signed my name to this specification in the presence of two subscribing witnesses.

HUGH DONOHOE.
